UNITED STATES PATENT OFFICE.

FRANK E. BESSLER, OF AKRON, OHIO, ASSIGNOR TO THE BESSLER MOVABLE STAIRWAY CO., OF AKRON, OHIO.

MOVABLE STAIRWAY.

1,088,960.

Specification of Letters Patent. Patented Mar. 3, 1914.

Application filed February 24, 1913. Serial No. 750,361.

To all whom it may concern:

Be it known that I, FRANK E. BESSLER, a citizen of the United States, residing at Akron, in the county of Summit and State 5 of Ohio, have invented a new and useful Movable Stairway, of which the following is a specification.

The device forming the subject matter of this application is a movable stairway of 10 that general type which is mounted to slide upon a hinged panel.

The invention aims to provide a movable stairway of the type above mentioned, which may be installed with a minimum disturbance 15 of the existing construction in the building.

The invention aims to provide a stairway which may be installed with a minimum expenditure of hardware.

It is within the scope of the invention to 20 improve a means whereby the panel is swung upon its pivotal mounting, and to provide a means whereby the stairway is slid upon the panel.

With the foregoing and other objects in view which will appear as the description proceeds, the invention resides in the combination and arrangement of parts and in the details of construction hereinafter described 30 and claimed, it being understood that changes in the precise embodiment of invention herein disclosed can be made within the scope of what is claimed without departing from the spirit of the invention.

In the drawing: Figure 1 is a side elevation 35 showing the panel swung downwardly, the stairway being lowered upon the panel; Fig. 2 is a transverse section showing the means whereby the links are assembled with the panel and with the frame which is closed 40 by the panel; Fig. 3 is a top plan showing the stairway in lowered position; Fig. 4 is a bottom plan showing the panel in closed position, the stairway having been elevated;

Fig. 5 is a side elevation showing the panel 45 in closed position; the stairway being elevated; Fig. 6 is a transverse section of the actuating drum; Fig. 7 is a longitudinal section of the actuating drum; Fig. 8 is a sectional detail showing the latch mechanism whereby the hand rail is upheld; Fig. 9 is a

plan of the latch mechanism depicted in Fig. 8; Fig. 10 is a transverse sectional detail showing means whereby the stairway is held upon the panel for sliding movement; Fig. 55 11 is a side elevation of the structure shown in Fig. 10; Fig. 12 is an elevation of one of the link supporting brackets; and Fig. 13 is a detailed perspective showing a portion of one of the stiles of the stairway. 60

In the drawing, the numeral 11 indicates a frame which is mounted in the ceiling 11^a.

The numeral 10 indicates a panel to the upper end of which are secured brackets 25 having extensions 26 which are pivotally connected with fixed hinge members 27 secured to the upper face of the ceiling 11^a. Through the coöperation of the parts above described, the panel 10 is mounted at one end for vertical swinging movement. 70

Supports 21 are secured to the upper face of the frame 11, and upon the supports 21 are mounted for vertical sliding movement, supports 20. Screws 20^a connect the support 20 and 21, to effect a vertical movement of the supports 20. In each support 20 is held a shaft 19, the shaft 19 being mounted to move in slots 21^a (see Fig. 12) formed in the fixed support 21. Links 14 are mounted to swing on the shaft 19, the links 14 being connected with links 12, by means of pivot elements 17, provided with set nuts 18. The lower ends of the links 12 are pivotally connected with brackets 12^a (see Fig. 14), the brackets 12^a being secured to the 80 panel 10. The links 12 are equipped with lateral fingers 12^b which extend across edges of the links 14, thereby to maintain the links as shown in Fig. 1, when the panel 10 is lowered. Sheaves 22 are carried by the 90 shaft 19 and about the sheaves 22 are trained cables 24. Each cable 24 is connected, as shown in Fig. 14 and as designated by the reference character 24^a, to one bracket 12^a. 95

Journalized in the brackets 25 are shafts 60, the shafts 60 being shouldered as indicated at 61, for engagement with the brackets 25. Each shaft 60 at one end is squared as shown at 60^a, to receive against rotation, a sheave 100 30. The cable 24 is trained about the periphery of the sheave 30, one end of each

cable being engaged as indicated at 24^a with the hub of the sheave and with the squared end 60^a of the shaft 60, so that the cable serves as a means for connecting the sheave 30 with the shaft 60.

Journaled for rotation upon the shaft 60 is a drum 29, provided at one end with a closure 29^a which may be held in place by screws 29^b or in any other desired manner.

- 10 Located within the drum 29 is a spiral spring 100, one end of which is secured as indicated at 101 to the drum 29, the other end of which is secured as indicated at 102 to the shaft 60. A cable 32 is trained about 15 the drum 29, in a direction opposite to that in which the cable 24 is trained around the sheave 30. The cables 32 are connected as indicated at 33 to a supporting rod 34, the rod 34 connecting the stiles 35 of the movable stairway 36.

The stairway 36 comprises the stiles 35 above mentioned, and steps 37 which connect the stiles. The stiles 35 are longitudinally slotted, as indicated at 39. Secured to the 25 panel 10 are angular guides 40, the extremities of which are received slidably in the slots. As shown in Fig. 11, the guides 40 are equipped with upstanding lugs 40^a having functions which will be set forth 30 hereinafter. Latches 42 are pivoted to the stiles 35 of the stairway, the latches 42 being adapted to engage with the lugs 40^a of the guides 40, to hold the stairway 36 in a retracted position or in an advanced one. 35 The stiles 35 slide upon rollers 38, carried by the panel 10. (See Fig. 10).

Hand rail supports 43 and 43^a are pivoted to one of the stiles 35, adjacent the upper and lower ends thereof, the hand rail support 43^a having a longitudinal groove 41, terminated at its upper end in a flared mouth 45. A bracket 47 is secured to the panel 10, the bracket 47 carrying a roller 46 which operates in the groove 41 of the support 43^a. 45 The hand rail 48 is pivotally connected with the upper ends of the supports 43 and 43^a.

A means is provided for maintaining the hand rail 48 in the uplifted position shown in Fig. 1, and in this connection, Figs. 8 and 50 9 may be examined with profit, in connection with Fig. 1.

Secured to one of the stiles 35 of the stairway 36 is a casing 49 in which is journaled a shaft 51 having a loop 52 adapted to engage with a projection 53 formed upon a support 54 connecting with the member 43. The shaft 51 may be manipulated by means of a key 51^a.

Supposing that the panel 10 is in a closed 60 position, and that the stairway 36 is elevated, the operation of the structure hereinbefore set forth is as follows: By drawing upon a flexible element 105 which is secured to the panel 10, the free end of the panel

may be swung downwardly, the panel 10 65 swinging upon the connected elements 26-27. When the panel 10 is swung into the depending position above described and shown in Fig. 1, the cables 24 will be drawn upon, rotating the sheaves 30 and rotating 70 the shafts 60, the springs 100 being put under tension. The stairway 36 is then drawn into a depending position, as shown in Fig. 1, the stiles 35 of the stairway sliding along the rollers 38, and the guides 40 moving in 75 the slots 39 of the stiles. When the stairway 36 is thus lowered, the flexible elements 32 will be reeled off the drums 29, the springs 100 being put under further tension. The hand rail 48 may thereupon be elevated into 80 the position shown in Fig. 1, under which circumstances, the roller 46 on the bracket 47 will enter the flaring mouth 45 of the slot 41 in the support 43^a and ultimately traverse the slot 41, the roller moving 85 into the position shown in Fig. 1. Through the medium of the key 51^a, the shaft 51 may be rotated until the loop 52 engages with the projection 53 which is fixed on the support 43, whereupon the hand rail 90 48 will be maintained in the uplifted position shown in Fig. 1. In order to elevate the stairway 36, the operation above described is reversed, and it is to be noted that by the downward swinging movement of the 95 panel 10 and by the downward sliding movement of the stairway 36 considerable tension has been imparted to the springs 100, so that these springs will aid materially in moving the panel 10 to a closed position, 100 and in elevating the stairway 36, upon the panel. The latches 42 engage with the lugs 40^a of the members 40 to hold the stairway 36 in uplifted position on the panel 10.

Having thus described the invention, what 105 is claimed is:—

1. In a device of the class described, a hingedly mounted panel; a stairway slidable upon the panel; a shaft supported by the panel; a sheave fixed to the shaft; a drum 110 rotatable upon the shaft; a spring connecting the drum with the sheave; a flexible element connecting the shaft with the panel; and a flexible element connecting the drum with the stairway.

2. In a device of the class described, a hingedly mounted panel; a stairway slidable upon the panel; a shaft supported for rotation adjacent the hinged mounting of the panel; a drum rotatable upon the shaft; a 115 spring connecting the drum with the shaft; a flexible element connecting the shaft with the panel; and a flexible element connecting the drum with the stairway.

3. In a device of the class described, a 120 hingedly mounted panel; a stairway slidable upon the panel coöperating elements comprising a shaft supported for rotation adja-

cent the hinged mounting of the panel and a drum rotatable upon the shaft; a spring connecting the drum with the shaft; a flexible element connecting one of said coöperating elements with the panel; and a flexible element connecting the other of said coöperating elements with the stairway.

In testimony that I claim the foregoing as my own, I have hereto affixed my signature in the presence of two witnesses.

FRANK E. BESSLER.
